UNITED STATES PATENT OFFICE.

OTIS A. MYGATT, OF NEW YORK, N. Y.

DESIGN FOR SHEET-GLASS OR SIMILAR ARTICLE.

42,422.

Specification for Design.

Patented Apr. 23, 1912.

Application filed July 1, 1909. Serial No. 505,495. Term of patent 14 years.

To all whom it may concern:

Be it known that I, OTIS A. MYGATT, residing at New York, in the county of New York and State of New York, have invented and produced a certain new and useful Design for Sheet-Glass or Similar Article, of which the following is a specification, reference being had therein to the accompanying drawings.

The design is intended for all types of transparent or translucent glassware.

Figure 1 is an elevation of one side of glassware embodying my design. Fig. 2 is an edge view of my glassware taken on the dotted line 2—2 of Fig. 1. Fig. 3 is an elevation of the reverse side shown in Fig. 1.

The design consists of parallel reflecting prisms on one side as shown in Fig. 1, facing waved flutes upon the opposite side as shown in Fig. 2.

The general appearance of my glassware is one of exceptional brilliancy, especially when used around inclosures of artificial lights the reflecting prisms on one side co-operating with the flutes on the other side to produce watered silk designs having a peculiarly rich appearance to the eye which it is impossible to show in a drawing.

I claim,

The ornamental design for sheet glass, or similar article, having on one side parallel series of reflecting prisms and on the other side lenticular waved flutes, substantially as shown and described.

OTIS A. MYGATT.
